BUCKET

Filed March 22, 1930

INVENTOR:
FRIEDA ANGELBECK.

BY *Arthur C. Ecket*
ATTORNEY.

UNITED STATES PATENT OFFICE

FRIEDA ANGELBECK, OF ST. LOUIS, MISSOURI

BUCKET

Application filed March 22, 1930. Serial No. 437,983.

The object of my device is to make a bucket that is convenient to be used in operation, such as cleaning, when it is necessary to have, for instance, clear water and soap water successively. With the conventional bucket, it is only possible to have either one of the liquids contained in it at a particular time. This means that two buckets are necessary in the simplest cleaning operation. Since it is not ordinarily practical to have more than one bucket at a time on a ladder, it requires the descent and ascent of the ladder each time that a different solution is necessary. By the use of my bucket, it will not be necessary to ascend and descend the ladder in the ordinary cleaning operation. My device may be made of few and simple parts that lend themselves readily to multiple production. With these and other objects in view my invention has relation to certain novel features of construction and arrangement of parts as will be hereinafter more fully described, pointed out in the claim and illustrated in the drawing, in which

25 Fig. 1 is a front elevation of one of the compartments used in my bucket.

Fig. 2 is a plan view of my completed bucket.

Fig. 3 is a side elevation of my completed bucket.

Fig. 4 is a sectional plan view on the line 4—4 of Fig. 3.

Fig. 5 is a fragmental elevation showing the jointure of the bucket handle to the bucket compartments.

Fig. 6 shows a modified form of my construction, which is the conventional bucket with a radial partition therein.

Numeral 7 indicates one of the compartments used in my bucket, which is in effect one half of the bucket, that is to say in plan it is semi-circular. It may be of conventional material, such as galvanized iron. To the top wall near the flat side is secured the ear 8 having the hole 9 formed therein. Two of such compartments such as 7, are placed together with the flat walls in contact. Numerals 10 designate hoops placed on the compartments, such as 7, for holding them together in the conventional manner. Numeral 11 des-

ignates a handle of the conventional shape with the exception that the free ends are bifurcated as shown at 12. I have projections for the insertion in the holes 9. I do not desire to be limited to a bucket of two compartments. A plurality of compartments may be used. Likewise, I do not desire to be limited to a bucket in which the compartments are secured together by hoops. Any conventional method, such as riveting, soldering, welding or nailing may be used. As a modified form, as shown in Fig. 6, I provide a conventional bucket having the radial partition 13 formed therein, which partition in effect divides the bucket into two compartments. A plurality of such partitions may be used for dividing the bucket into a plurality of compartments.

What I claim is—

A bucket comprising compartments secured together by hoops, perforated ears formed on each compartment, a handle having bifurcated ends with projections formed on each bifurcated end for engagement in the perforated ears, the bifurcated ends of said handle being in engagement with the perforated ears on adjacent compartments.

In testimony whereof I affix my signature.

FRIEDA ANGELBECK.
